CLAIM

The ornamental design for a solar tile, as shown and described.

DESCRIPTION

FIG. 1 is a perspective view of a solar tile showing our new design;

FIG. 2 is a front view thereof;

FIG. 3 is a rear view thereof;

FIG. 4 is a left view thereof;

FIG. 5 is a right view thereof; and,

FIG. 6 is a top view thereof.

The broken lines illustrate the portions of the solar tile that form no part of the claimed design.
